ULRICH BISCHOF, OF HOREN, SWITZERLAND, ASSIGNOR TO GEBR. STAUBLI, OF HOREN, SWITZERLAND.

LAYING-ON APPARATUS FOR BOOK-FASTENING MACHINES.

Application filed December 13, 1920. Serial No. 430,353.

To all whom it may concern:

Be it known that I, ULRICH BISCHOF, a citizen of Switzerland, residing at Horgen, in the canton of Zurich and Republic of Switzerland, have invented certain new and useful Improvements in Laying-On Apparatus for Book-Fastening Machines, of which the following is a specification.

In the known book fastening machines comprising one or more movable worktables, the sheets must be laid at the proper time upon the worktable when the latter is in its extreme position. It is obvious that the output of the machine is very considerably dependent upon the attention and the skill of the operator laying on the sheets, because there is only a very short time available in each working cycle of the machine, for laying the sheet on to the moving worktable of the machine.

With the improved laying-on apparatus, the time available for this purpose is much longer, so that the above mentioned drawbacks are obviated or at least considerably diminished.

According to this invention the machine is provided with an auxiliary table upon which the sheets are laid during the working cycle of the machine table. The sheets situated upon the auxiliary table are then transferred by a conveyor automatically on to the machine table where they are adjusted into their proper position immediately the latter has assumed the suitable position for this purpose.

The accompanying drawings illustrate by way of example an embodiment of the improved laying-on apparatus in combination with a machine for fastening the sheets together by means of thread.

Fig. 1 is a side elevation thereof viewed in the direction of the arrow B in Fig. 2.

Fig. 2 is a front elevation viewed in the direction of the arrow A in Fig. 1, and

Fig. 3 is a side elevation viewed in the direction of the arrow C in Fig. 1.

Fig. 4 is a side elevation of the slide block, and

Fig. 5 is a front elevation thereof.

1 is the machine frame; 2 is the main shaft mounted in the latter, with the cam 3 in which there engages an anti-friction roller 5 carried by the rocking lever 4. The shaft 2 is carried in bearings in the frame 1.

55 The driving pulley is not shown. The shaft

7 that carries the rocking lever 4 rests in bearings 8 in the frame. This lever carries at its free end a rope pulley 9 for a purpose hereinafter described. On a shaft 10 mounted in the machine frame there is fixed by means of the arms 18, 19, the machine table 11 in which the rod 12 is mounted together with the thread layer 13 required for forming the knot. The piercing needles, not shown, are also mounted in the machine table.

On the machine table 11 there is supported in a bracket 20, a rod 21 on which are fixed four fingers 22 and levers 23, 24. A spring 25 fixed at one end to the table 11 and at its other end to the lever 23, has a tendency to press the lever 24 against a stop 27 fixed on the hereinafter described shaft 26. In the bracket 20 there is mounted a rod 27 slidable in the direction of its length, which carries an arm 28, an arm 30, and a sheet stop 29. The rod 27 is rotated by a spring 31 (fixed at one end to the bracket 20), in such a manner that the sheet stop 29 presses against the table surface. The arm 28 carries a roller 32 which bears upon the cam 34 fixed to the stitching bar 33. This cam causes in the inward and outward strokes of the machine table 11, a movement of the rod 27, and consequently of the sheet stop 29 together with the arm 30.

On the machine frame 1 there is arranged by means of a bracket 35, an angle-shaped auxiliary table 36. In this bracket there is also mounted a rod 37 on which there is situated a compression spring 38 and a set collar 40 that serves as a stop for the said spring. In the bracket 35, as well as in a bracket 41 fixed to the other end of the machine frame, there is mounted the hereinbefore referred to shaft 26 with spring 42, the latter bearing at one end against the stop 27' and at its other end against a slide block 43. This slide block has a downwardly directed guide arm 39 engaging over the rod 37, and slides by means of a rib in a groove 41' in the auxiliary table 36, as well as in a groove 43' of the machine table 11, connected to the groove 41'. A clutch 44 serves to couple a wire rope 45 to the slide block 43. This wire rope passes over the guide pulleys 46, 47 mounted on the left portion of the machine frame, and also over the aforesaid pulley 9 mounted on the rocking lever 4, and it terminates at a pin 48 fixed to the said rock-

ing lever. From the foregoing it will be understood that the oscillations of the lever 4 will cause through the medium of the wire rope 45, the slide block 43 to move to and fro.

The needle apparatus for fastening together the sheets with thread consists of the needle bars 49 guided in the bracket 46' with the needles 53. The needle bars receive an 10 up-and-down motion in the usual manner.

The operation of the apparatus is as follows:—

The sheet 51 to be fastened is laid by the operator upon the fixed auxiliary table 36 15 whilst the machine is in operation. Then in a known manner (not forming part of this invention) the machine table 11 receives a rocking motion around the axis 10. The arrangement is such that when the table 11 20 assumes the position shown in Figs. 1 and 2, the cam 3 will cause the rocking lever 4, 5 to assume its lowest position, and through the medium of the rope 45 the slide block 43 will be moved quickly to the left. This 25 slide block in its turn pushes the sheet 51 lying on the auxiliary table 36, out of the position shown in full lines over on to the machine table 11 where it strikes against the stop 29 mounted on the rod 27 (see position 30 shown in broken lines). Immediately thereupon the slide block 43 is moved by the spring 42 back into its former position on the auxiliary table 36. This is made possible by the fact that the cam 3 raises the 35 arm 5 with the roller 9 and thus loosens the wire rope. When the slide block 43 is again approaching its extreme right hand position on the auxiliary table, one of the two stops 49' of the former engages underneath the 40 sheet which has been laid in the meantime by the operator upon the auxiliary table and bears against the stop 50 (Figs. 1, 3 and 5). The stop 49' now slides underneath the sheet, so that in the next left hand stroke of the slide block 43, the sheet will be taken 45 along by its upwardly directed stop 52.

When in the first mentioned left hand stroke of the slide block 43, the sheet has 50 reached the stop 29, the machine table 11 is caused to begin its inward rocking movement in the usual manner, so that the roller 32 mounted on the arm 28 slides along the cam 34 with the result that the rod 27 carrying the arm 28, is moved together with the 55 stop 29 a slight distance to the right. This small movement is designed for the purpose that if the sheet should have jumped back owing to its previous striking against the stop 29, the said sheet will be pushed by the 60 last mentioned short right hand movement, into its proper position on the machine table.

When this is done, the fingers 22 fixed on the rod 21 press the sheet that has just been laid in, against the table or its top edge, in 65 order that it shall not be liable to become

shifted. This is effected by the fact that the arm 24 fixed on the rod 21, in the inward rocking movement of the machine table 11, leaves the stop 27' that is mounted on the rod 26, whereupon the spring 25 by means of the lever 23 turns the rod 21 to such an extent that the fingers 22 will press the sheet against the table.

When the machine table 11 has come into its innermost position, the needle apparatus 75 effects in the usual manner the fastening of the sheets, whereupon the table 11 is moved again outwards, and the cycle of operations begins anew.

As already mentioned in the beginning hereof, the operator has to lay the sheet to be fastened on to the auxiliary table 36, whence it is brought automatically on to the machine table. By this means the above 80 mentioned advantages are obtained. It is to be understood that the laying of the sheets upon the auxiliary table may also be effected by a mechanical feeding apparatus.

What I claim is:—

1. In a book fastening machine, the combination of a movable machine table upon which the sheets to be fastened are laid, with an auxiliary table for receiving the fresh sheets, a slide block for conveying the fresh sheets from the auxiliary table on to the machine table, means for moving said slide block to-and-fro, and movable stops on the machine table for adjusting the sheets in their proper position on the machine table.

2. In a book fastening machine, the combination of a movable machine table, with a stationary auxiliary table, a slide block for conveying the fresh sheets from the auxiliary table on to the machine table, and rocking arms mounted on the machine table for holding down the sheets conveyed on to the said machine table.

3. In a book fastening machine, a movable machine table, a stationary auxiliary table, having grooves, a slide block movable over both tables for conveying the fresh sheets, said slide block having wedge-shaped extensions sliding in the grooves in said auxiliary table, and having also an upwardly directed stop, whereby, when the slide block is moving toward the auxiliary table the said extensions engage under the sheet located thereon, and thus produce a sliding of the slide block underneath said sheet, and in the successive movement of the slide block towards the machine table, the stop carries along with it the sheet that is movable on the auxiliary table.

4. In a book fastening machine, a movable machine table, a stationary auxiliary table, a slide block slidable over both tables, a stationary rod on which the slide block is slidably mounted, a compression spring mounted on said rod, a flexible tensile device, grooved rollers for guiding the tensile device, a rock-

ing lever with anti-friction roller, and a cam for operating said rocking lever, one end of the tensile device being connected to the slide block, and its other end being connected to the rocking lever.

5. In a book fastening machine, a rocking machine table, a shaft mounted thereon, spring-controlled arm fixed on said shaft, for pressing the sheets down upon the machine table, a lever fixed on said shaft, and a stop located on the machine frame for the last mentioned lever.

10. In a book fastening machine, a rocking machine table, a rod slidably mounted there-

on, a stop fixed on said rod for the sheets that have been conveyed on to the machine table, a compression spring for bringing the stop into a determined position, an arm fixed on said rod, carrying an anti-friction roller, and a fixed cam along which the anti-friction roller slides when the machine table rocks forwards, for the purpose of placing the sheet that has been conveyed from the auxiliary table on to the machine table, into the proper position on said machine table.

15. In testimony whereof I have affixed my signature.

ULRICH BISCHOF.
